UNITED STATES PATENT OFFICE.

WARREN L. CORT, OF FLATBUSH, NEW YORK.

DESIGN FOR A GAS-STOVE.

SPECIFICATION forming part of Design No. 22,429, dated May 9, 1893.

Application filed March 11, 1893. Serial No. 465,645. Term of patent 7 years.

To all whom it may concern:

Be it known that I, WARREN L. CORT, of Flatbush, Kings county, and State of New York, have invented and produced a new and original Design for Gas-Stoves, of which the following is a specification, reference being had to the accompanying drawing, forming part thereof.

The drawing is a front elevation of the front of the stove.

The leading feature of my design consists in the continuous band of tiles *a* extending along the sides and across the top of the opening in the front of the stove, forming a border or frame for the opening. Around each edge of the tile are the borders *b* and *c* standing out from the surface of the tile and complet-

ing the effect of the frame. At the bottom of the tiles are scrolls *d d*, having between them the fan-like piece *d'*, the whole forming the lower side of the frame. Above the upper band of the tile is a band of foliated work *e* and above that, the double scrolls *ff* forming the irregular top line *g*.

Heretofore, in stove designs the band of tile has been divided so as to form detached sections and not a continuous band.

What I claim is—

The design for gas stoves as herein described and shown.

WARREN L. CORT.
